UNITED STATES PATENT OFFICE.

ELLWOOD A. METZ, OF GLENARM, MARYLAND, ASSIGNOR TO F. X. HOOPER COMPANY, OF GLENARM, MARYLAND, A CORPORATION OF MARYLAND.

CUTTING ATTACHMENT FOR PRINTING PRESSES.

Application filed July 8, 1924. Serial No. 724,817.

To all whom it may concern:

Be it known that I, ELLWOOD A. METZ, a citizen of the United States, residing at Glenarm, in the county of Baltimore and 5 State of Maryland, have invented certain new and useful Improvements in Cutting Attachments for Printing Presses, of which the following is a specification.

This invention relates to an attachment 10 for printing presses of the type adapted to print upon heavy stock, such as box blanks of strawboard and the like, and it comprises means, arranged at the delivery end of the press, and timed to the movements 15 of the press, for cutting off the ends of certain flaps on the blank as they issue from the press. The blanks are slotted to form flaps upon a suitable slotting machine before being fed into the printing press, and as 20 they issue from the press the printing rollers serve as a means for feeding the blanks to the cutting mechanism. This cutting mechanism comprises rotary cutters arranged upon two parallel shafts located close to 25 the printing cylinders and geared to the power shaft of the press, one of these shafts being vertically movable to carry the cutters thereon into and out of engagement with the cutters on the opposing shaft, and mechanism 30 for automatically depressing and raising the movable shaft at the proper times to cause the cutters to cut certain flaps and to allow other flaps to pass between the cutters without being cut. The movable 35 cutter shaft is actuated positively and instantly in both directions by mechanism which includes a cam carrier driven from the power shaft of the press and therefore timed to the movements of the printing 40 cylinders, which constitute the feeding mechanism for the box blanks.

By means of this attachment, the operation of cutting alternate flaps on the box blanks is performed on the printing 45 press, thereby making it unnecessary to pass the blanks through a separate machine for this purpose.

In the accompanying drawing,

Fig. 1 is a side elevation of the delivery 50 end of a full rotary printing press for printing on box blanks, having my flap-cutting attachment thereon;

Fig. 2 is a plan view illustrating a box blank before its passage through the press, 55 the dotted lines indicating lines on which

certain of the flaps will be cut off when the blank is operated upon by the cutting attachment;

Fig. 3 is a top plan view of the delivery 60 end of the press, with my attachment thereon, parts being broken away to show the cutters and operating mechanism;

Fig. 4 is a vertical section on the line 4-4 of Fig. 1; and,

Fig. 5 is a side elevation of the attachment, with the gears removed.

Referring to the drawing, *a* represents the frame of a printing press suitable for printing upon heavy stock, such as strawboard, fiber, wood, etc., and *b* represents a 70 printing or form cylinder arranged above the bed 1 of the press. This cylinder co-operates with an impression cylinder, indicated at *c* in dotted lines in Fig. 1, to make the printed impressions upon the stock 75 as it passes along the bed, from left to right, in Fig. 1, and the printed stock is carried from the bed by a tape delivery indicated by the dotted lines 2. The press may have one or more additional form cylinders for 80 printing in different colors, and is provided with suitable means (not shown) for feeding and moving the stock along the bed. The drive shaft for the mechanism shown is indicated at *d*. This shaft carries a pinion 85 3 which meshes with a gear 4 on a shaft 5, which is journaled in the frame of the machine, and a gear 6 is secured to the opposite end of this shaft. This gear 6 meshes with a gear 7, shown in dotted lines, and 90 the latter meshes with a gear 8 which, in turn, meshes with a gear 9, on a shaft 10 which supports the form cylinder. The ratio of gearing between the shafts 5 and 10 is such that the peripheral speed of the 95 form cylinder will be the same as that of the impression cylinder which is carried on the shaft 5.

The attachment which I have provided for cutting the flaps of box blanks after 100 they have been printed upon is mounted close to the form and impression rollers so that the latter feed the blanks directly to the cutting apparatus. This cutting apparatus comprises a cutter shaft 11, journaled in the sides of the frame and having rotary cutter knives 12 which are adapted 105 to co-operate with complementary knives 13 on a cutter shaft 14, which is mounted in the ends of a pair of swinging arms 15 and 15^a, 110

which arms are pivotally mounted upon brackets 16 and 16^a, at the opposite sides of the press. The cutters on both cutter shafts are driven at the same speed by trains 5 of gearing from the pinions 3 on the drive shaft *d*. Thus, a gear 17 engages the gear 3 and is, in turn, engaged by a gear 18, which latter meshes with a gear 19 on the cutter shaft 11 and with a gear 20, which 10 is mounted upon a shaft 21. The gear 20 meshes with a gear 22 which is mounted upon a fixed stud 23, secured to the bracket 16, this stud also serving as a pivot for the swinging arm 15 and being in line with the 15 axis of the swinging arm 15^a. The gear 22 meshes with a wide gear 24, pivotally mounted on a stud 25, projecting from the central portion of the arm 15, and the gear 24 meshes with a gear 26 on the end of the 20 cutter shaft 14.

Thus, by the gearing described, when the drive shaft *d* of the press is rotated, the printing and impression cylinders as well as the cutters will be operated at the same 25 circumferential speed.

Rods 27, secured to the arms 15 and 15^a, near their free ends, extend upwardly through guides 28 on brackets 29 and 29^a, fixed to the sides of the machine, and cushioning springs 30 are mounted on the guides and tend to lift the guide rods and the swinging arms upwardly to disengage the cutters on the movable shaft 14 from the cutters on the stationary shaft 11. Each 30 swinging arm has its free end connected to the adjacent bracket by toggle levers *t*, which depend from the bracket to the end of the arm. The pairs of toggle levers are flexed and straightened by means of links 31, connected to the centers of the pairs and to vertically arrange levers 32, mounted upon a rock shaft 33. This rock shaft is 35 at the rear and below the bed of the press and carries both of the levers 32. Upon the rock shaft is mounted a short arm or lever 34 which projects substantially at right angles to the levers 32, and this arm or lever 34 is connected by a depending link 35 to the end of an operating lever *f*, which 40 is pivotally mounted upon a bracket 36. The longer arm of the lever is connected to the link 35, and the shorter arm 37 is of triangular shape, as shown, and carries rollers 38 and 39, the former above and the latter below the axis of the lever.

A cam wheel *g* is horizontally arranged in the plane of the axis of the operating lever and is mounted to turn in said plane upon a central shaft 40, which is vertically mounted in a base *h*, below the cam wheel. This base carries a suitable number of guide wheels 41, some arranged above and some below the wheel, which bear upon the wheel near its periphery and steady the wheel. The shaft 40 is geared to the shaft 3, which

drives the form and impression cylinders, so that the cam wheel will be rotated in time with the rotation of the printing members, which, as before stated, serve as a means for feeding the blanks to the cutters. 70 The gearing connecting the cam wheel with the shaft 3 comprises a spiral pinion 42 on the shaft 3, which engages a spiral gear 43 on a shaft 44, which extends at right angles to the shaft 3 and carries a spiral pinion 45, 75 meshing with a spiral gear 46, mounted upon the shaft 40 which carries the cam wheel.

The cam wheel has on its upper side, near its periphery, an undercut groove 47, 80 and on its lower side it has a similar groove 48, (Figs. 1 and 3). Cams 49 and 49^a are held upon the upper side of the wheel over the groove 47 by clamping bolts 50, having wide heads which fit within the groove. 85 These cams can be adjusted to any desired positions about the circumference of the wheel. Similar cams 51 and 51^a are arranged upon the underside of the cam wheel and are similarly held by clamping bolts 90 fitting within the groove 48, and these lower cams are also adjustable to any desired positions about the circumference of the cam wheel. The cams upon the upper side of the cam wheel are adapted to engage the 95 roller 38 to rock the operating lever *f* in one direction, and the cams 51 and 51^a are adapted to engage the roller 39 and rock the operating lever in the opposite direction. When one of the upper cams rocks the operating lever by engagement with the roller 38, it will be evident that through the system 100 of links and levers connected with the operating arm, the toggle levers *t* will be straightened and the shaft 14, carrying the upper cutter wheels, will be pressed downwardly into cooperative engagement with the lower cutter wheels. When one of the 105 cams on the lower side of the cam wheels rocks the operating lever, the toggle levers 110 will be flexed, as shown in Fig. 5, and the shaft carrying the upper cutter wheels will be raised out of engagement with the lower cutters. The arrangement of levers is such 115 that a slight movement of the operating lever by a cam will cause a relatively long movement of the link 31, and this movement is sufficient to move the upper cutter wheels into cutting engagement with the lower wheels when the toggles are straightened 120 and to raise the upper cutter wheels sufficiently to permit the box blanks or stock to pass through to the end of the bed without being cut. The cams move the operating 125 lever positively in both directions at precise times in the movement of the wheel and of the blank, and by setting the stops in the proper positions, the cuts in the blank may be made to commence and end at any desired 130 points in their lengths. The springs 30

130

are not relied upon to raise the arms 15, carrying the upper cutter shaft, but are used as counterbalance springs to take up the shock and make the apparatus work more smoothly.

A box blank *j*, indicated in Fig. 2, is shown as having slots 52, 53 and 54, cut transversely in its opposite edges. These blanks, cut to suitable size and slotted as shown to form flaps, are fed endwise into the printing press by suitable feeding mechanism, not shown, and as the blanks pass between the form roller and the impression roller, the blanks are printed with any desired printed matter, and these rollers feed the blanks rearwardly between the cutter shafts and on to the tape delivery 2, which carries them away from the press. It will be obvious that by suitably locating the cam blocks on the cam wheel, the upper cutter shaft may be raised and lowered, as desired, to make spaced cuts in the blanks. Thus, to cut off the flaps 55 on the blank shown in Fig. 2, a cam will be located on the upper side of the cam wheel in such position as to cause the cutters to be in cutting engagement when the blank, moving in the direction of the arrow, reaches the cutters, and a cam will be placed on the lower side of the cam wheel in such position as to rock the operating lever in the direction to flex the toggle at the moment when the flaps 55 are cut off along the lines 55^a. The cutters will remain separated while the flaps 56 are passing between them, and a properly positioned cam on the top of the cam wheel will then rock the operating lever to straighten the toggles and depress the upper cutter shaft, and the cutters will then cut off the ends of the flaps 57, along the lines 57^a. A properly positioned cam on the underside of the cam wheel will then rock the operating lever to flex the toggles and lift the cutter shaft while the flaps 58 are passing between the wheels. The cutter wheels, as usual, in rotary cutting machines, may be adjusted along their shafts to cut the blanks at different distances from their lateral edges, and the longitudinal cuts or incisions may be made to any desired length and at any desired distance apart longitudinally of the blank to cut the flaps of box blanks of various sizes and designs.

What I claim is:

1. The combination with a printing press for printing on box blanks, including a form cylinder, of cutters at the delivery end of the press adapted to cut the blanks, and means, timed to the movement of the cylinder, for intermittently raising and lowering the cutters.

2. The combination with a printing press for printing on box blanks, including a form cylinder, of rotary cutters at the delivery end of the press adapted to cut the blanks,

and means, timed to the movement of the cylinder, for intermittently raising and lowering the cutters.

3. The combination with a printing press for printing on box blanks, including a form cylinder, of parallel shafts arranged transversely of the bed at the rear of the form cylinder and having co-acting cutters for cutting the blanks, and means, timed to the movement of the cylinder, for intermittently moving one of said shafts toward and from the other shaft.

4. The combination with a printing press for printing on box blanks, including a form cylinder, of two cutter shafts, adjacent said cylinder, said shafts having co-acting cutters thereon, gearing connecting said shafts with the press-driving mechanism, and means, timed to the operation of the form cylinder, for raising and lowering one of said shafts.

5. The combination with a printing press for printing on box blanks, including a form cylinder, of two cutter shafts adjacent said cylinder, cams operated by the press-driving means, and means operated by said cams for raising and lowering one of said shafts.

6. The combination with a printing press for printing on box blanks, including a form cylinder, of two cutter shafts adjacent said cylinder, toggle levers for raising and lowering one of said shafts, and means timed to the operation of said cylinder for flexing and straightening the toggle levers.

7. The combination with a printing press for printing on box blanks, of two cutter shafts arranged transversely of the press at its delivery end, toggle levers for raising and lowering one of said shafts, a cam carrier geared to operate in time with the press and having cams thereon, and means actuated by the cams for flexing and straightening the toggle levers.

8. The combination with a printing press for printing on box blanks, of two cutter shafts arranged transversely of the press at its delivery end, toggle levers for raising and lowering one of said shafts, a cam wheel geared to operate in time with the press, cams adjustably secured to opposite sides of said wheel, an operating lever adapted to be rocked by said cams, and connections between said operating lever and the toggle levers for flexing and straightening the latter.

9. The combination with a printing press for printing on box blanks, of two cutter shafts arranged transversely of the press at its delivery end, toggle levers for raising and lowering one of said shafts, a cam wheel adapted to turn in a horizontal plane and geared to operate in time with the press, cams on the upper and lower sides of said wheel, an operating lever pivoted to rock in a vertical plane and having parts ar-

ranged to be engaged by said cams, and connections between said operating lever and the toggle levers for flexing and straightening the latter.

5 10. The combination with a printing press for printing on box blanks and comprising a horizontal bed, a drive shaft and form and impression cylinders geared to said shaft so as to be positively driven thereby, of cutters

at the delivery end of the press, and mechanism geared to said shaft, and timed to the movement of the form cylinder, for causing said cutters to intermittently engage and cut the blanks.

10 In testimony whereof I hereunto affix my 15
signature.

ELLWOOD A. METZ.
